UNITED STATES PATENT OFFICE

RUTH GERTH, OF NEW YORK, N. Y., ASSIGNOR TO THE CHASE COMPANIES, INCORPORATED, OF WATERBURY, CONNECTICUT, A CORPORATION

DESIGN FOR A RECEPTACLE FOR ASHES AND OTHER MATERIAL

Application filed March 5, 1932. Serial No. 43,093. Term of patent 14 years.

To all whom it may concern:

Be it known that I, RUTH GERTH, a citizen of the United States, residing at New York, in the county of New York and State of New York, have invented a new, original, and ornamental Design for a Receptacle for Ashes and Other Material, of which the following is a specification, reference being had to the accompanying drawings, forming part thereof.

Fig. 1 is a side view of a receptacle for ashes and other material showing my new design; and

Fig. 2 is a top view of the same.

I claim:

The ornamental design for a receptacle for ashes and other material as shown.

RUTH GERTH
